UNITED STATES PATENT OFFICE.

CEYLON C. WALCH, OF SYRACUSE, NEW YORK.

ATTACHMENT FOR LANTERNS.

Application filed June 14, 1926. Serial No. 115,829.

This invention relates to an attachment for lanterns to be used in connection with standard forms of lanterns commonly employed for railway traffic signal purposes and analogous uses.

These lanterns are usually provided with transparent or translucent globes of different conventional colors such as "clear", "amber", "green" and "red", each having 10 a different significance and requiring the use of different lanterns for different signals.

The main object is to provide a simple and efficient attachment which, when placed in operative position upon the frame of the lantern, will permit the same lantern to be 15 used for the various conventional signals.

One of the specific objects is to provide means whereby the colored signal plate may be alternately exposed and concealed as may 20 be required to give either a clear signal or a colored signal from the same lamp.

Another object is to provide means whereby the supporting frame for the plate may be easily and quickly attached to or detached 25 from the frame of the lantern without displacing any of the parts of the lantern.

Other objects and uses relating to specific parts of the attachment will be brought out in the following description.

In the drawings:—

Figure 1 is a front face view of a standard form of lantern equipped with my attachment.

Figure 2 is an enlarged vertical sectional view taken on line 2—2, Figure 1.

Figure 3 is a perspective view of the detached attachment.

In order that the invention may be clearly understood I have shown a standard form 40 of lantern comprising a base —A— having a burner —a— as the source of light and a transparent globe —B— of glass or other suitable material held in place upon the base —A— by means of superposed hinged cover 45 or cap section —C—.

The base —A— is mounted in a suitable supporting frame which serves as a guard for the fuel tank and globe and comprises a base ring —D—, a top ring —d—, an intermediate ring —d'— and upright guard members —d''— together with suitable 50 ventilating pipes —E— and legs —e— carried thereby.

The lower ends of the guard members are 55 attached to the base ring —D— in circumferentially spaced relation midway between

the ventilating pipes —E— and serve as convenient means for holding the attachment against circumferential displacement.

The lantern attachment forming the subject matter of this invention comprises a main supporting frame —1— having a base —2— and upright guides —3— together with suitable means such as bolts —4— and nuts —5— for clamping and releasing the attachment to and from the base ring —D—.

The frame —1— is of sufficient height to extend from the base ring —D— to the top ring —d— and is provided with a stationary opaque plate 6 which together with the upright guides —3— are preferably made of sheet metal and integrally connected to each other.

The front plate —6— constitutes a shield and extends approximately half the width 75 of the frame or when placed upon the lantern extends from the base ring —D— to a level slightly above the burner —a— where it terminates to form a sight opening —7— of approximately the same area as the shield 80 —6—.

The upright guides —3— are arranged in transversely spaced relation and extend upwardly some distance above the upper edge of the shield —6— and are provided with 85 grooves —8— open at their inner sides and facing each other for receiving a colored signal plate —9— of glass or other suitable material.

This signal plate —9— is of about the 90 same area as the shield —6— and sight opening —7— and is movable from a position below the upper edge of the shield —6— with its lower edge resting upon the base portion —2— of the frame —1— to a position mainly above said shield and across the opening —7— so that when dropped to its lower position it will be concealed from view and allow the rays of light to pass directly from the burner —a— through the globe —B— and out through the opening —7— without obstruction or material diminution thus permitting the lantern to be used in the usual manner for "clear" 95 signaling.

On the other hand, the signal plate —9— may be adjusted vertically across the opening —7— to give the desired conventional color signal in that the rays of light from the burner —a— will then be transmitted 100 through the colored signal plate —9—.

The means for effecting the upward move-

ment and controlling the downward movement of the signal plate —9— consists in this instance of a stop bolt —10— movable in a vertical slot —11— in the shield —6— and provided with an external hand piece —12— and a brake member —13— which is spring-pressed into engagement with the shield —6— by a coiled spring —14—, Figure 2.

10. The upper end of the slot —11— is provided with a laterally and downwardly extending offset —15— into which the bolt —10— may be moved to hold the signal plate —9— in its uppermost or operative position.

15. The clamping bolts —4— are passed through suitable apertures —16— in the base —2— near the opposite ends thereof and have their front ends provided with hooks —17— for engaging the adjacent portions 20 of the base ring —D— as shown in Figure 2.

These bolts when sufficiently loosened may be moved endwise and turned about their axes to engage and disengage the hooks —17— with and from the adjacent portions 25 of the ring —D— when it is desired to remove the attachment from the lantern.

When placing the attachment in operative position upon the lantern its upper portion is inserted from the underside upwardly behind 30 the front portion of the intermediate —d'— until its upper end assumes a position just at the rear of the front portion of the upper ring —d— or rather with the front portion of the marginal flange of the cover —C— 35 which serves to hold the upper portion of the frame against lateral and forward and rearward movement relatively to the cover, sufficient clearance being left between the top of the cover and upper end of the frame to 40 allow the lower end of the attachment to be moved rearwardly over the top of the base ring —D— after which the hooks —17— of the bolts are turned so as to hook over and upon the ring —D— with the bolt resting 45 on the upper edge of the ring when the lower end of the frame —1— is allowed to drop in behind said ring after which the nuts —5— are tightened to clamp the lower end of the frame —1— against the inner face of the 50 ring —D— and at the same time drawing the hooks —17— against the front face of the ring.

When a "clear" signal is desired the signal plate —9— may be dropped to its lower 55 most position while on the other hand if a colored signal is desired the signal plate will be adjusted to its uppermost position.

The upper ends of the guides —8— are open to permit the insertion and removal of 60 the signal plate —9— and also to permit said plates to be changed at will when desired to give different colored signals.

What I claim is:

1. A signal supporting attachment for lanterns comprising a frame having opposite 65 parallel guides in spaced relation, an opaque shield across the lower portion of the space between the guides leaving an opening above the shield, and a translucent signal plate movable lengthwise in the guides from a position across the shield to a position across the opening above the shield, adjustable means for holding the signal plate in its elevated position and permitting it to be lowered to a position across the shield, and 70 movable means on the lower end of the frame for clamping said frame to a base portion of the lantern.

2. A signal supporting attachment for lanterns comprising a frame having a base portion, an opaque shield portion, guides extending upwardly from opposite ends of the base along and above opposite upright edges of the shield portion to form an opening above said shield portion, said shield portion being provided with an upright slot having a lateral offset at its upper end, a translucent signal plate slideable vertically in said guides to and from a position mainly below the upper edge of the shield and to 80 and from a position mainly above the upper edge of the shield, means movable in said slot and its offset for engaging and holding the signal plate in its elevated position and permitting it to be moved to its lowermost position, and adjustable bolt hooks mounted on the base portion of the frame for clamping said base portion to the lower portion of the frame of the lantern.

3. A signal supporting attachment for lanterns comprising a frame having a base portion, an opaque shield portion, guides extending upwardly from opposite ends of the base along and above opposite upright edges of the shield portion to form an opening 100 above said shield portion, said shield portion being provided with an upright slot having a lateral offset at its upper end, a translucent signal plate slideable vertically in said guides to and from a position mainly below the upper edge of the shield and to 105 and from a position mainly above the upper edge of the shield, means movable in said slot and its offset for engaging and holding the signal plate in its elevated position and permitting it to be moved to its lowermost position, and adjustable bolt hooks mounted on the base portion of the frame for clamping said base portion to the lower portion of the frame of the lantern, said guides consisting of grooves 110 in opposite sides of the frame open at the top to permit the removal and replacement of the signal plates endwise therethrough.

In witness whereof I have hereunto set my hand this 7th day of June, 1926.

CEYLON C. WALCH.
